United States Patent Office

Des. 183,223
Patented July 15, 1958

183,223

GOLF PRACTICE DEVICE

James R. Neiler, Olean, N. Y.

Application November 18, 1957, Serial No. 48,503

Term of patent 14 years

(Cl. D34—5)

Fig. 1.

Fig. 2.

Fig. 1 is a perspective view of a golf practice device, showing my new design; and

Fig. 2 is a side elevational view thereof.

I claim:

The ornamental design for a golf practice device, substantially as shown.
